UNITED STATES PATENT OFFICE.

FRANK M. ASHLEY, OF NEW YORK, N. Y., ASSIGNOR OF ONE-HALF TO
ALBERT T. SCHARPS, OF NEW YORK, N. Y.

GAS-BURNER.

No. 838,156.

Specification of Letters Patent.

Patented Dec. 11, 1906.

Application filed May 25, 1899. Serial No. 718,242.

To all whom it may concern:

Be it known that I, FRANK M. ASHLEY, a citizen of the United States, residing at New York city, in the county of Kings and State 5 of New York, have invented certain new and useful Improvements in Gas-Burners, of which the following is a full, clear, and exact specification.

This invention relates to gas-burners, and 10 has particular reference to burners used for the burning of acetylene gas and other gases rich in hydrocarbon.

The invention is particularly applicable 15 for burning gas for heating purposes.

The object of the invention is to provide a burner which shall thoroughly intermix the 20 gas with air and burn the mixture. I have found that if the gas can be burned in cylindrical form the air on the inside of the cylinder 25 becoming heated is intermixed with the flame, and I therefore desire by this invention to provide a burner which will burn gas in such a way as to produce a cylindrical flame.

The invention comprehends various other 30 features of advantage, which will more clearly appear hereinafter and will be pointed out in the accompanying claims.

In the drawings, in which I have illustrated 35 various forms which the invention may take in practice, Figure 1 is a sectional view of a burner constructed in accordance with my invention. Fig. 2 is a similar view of a modification. Fig. 3 is a top view of a still further modification. Fig. 4 is a side view of the burner shown in Fig. 3, and Fig. 5 is a sectional view of the same burner.

Referring more particularly to the drawings, 1 represents a suitable body portion having a screw-thread 2 or other means for 40 attaching the same to a pipe or other source of gas-supply. The body portion 1 is provided with an outwardly-flaring annular rim or flange 3, thereby forming in the body portion a bell-shaped opening. Near the base of 45 the bell-shaped portion 4^a at intervals are formed a number of air-inlet openings 4. Preferably, for a purpose to be hereinafter described, I also form in the lower part of the bell-shaped portion, which is a continuation 50 of the passage 6, to be hereinafter described, an annular chamber 5, into which the said openings 4 discharge, as illustrated in Fig.

2. A plug 3^a, having a cone-shaped head, is adapted to fit tightly into the body portion 1, as illustrated in the drawings, the cone-shaped head being substantially the same shape as the flange portion 3 of the body portion 1, whereby an annular mixing-passage 6 will be formed between the plug and bell-shaped opening. In the lower end of the 60 plug 3 is formed an axial chamber 7 in communication with the source of gas-supply, and from the chamber 7 a number of gas-passages 8 lead into the passage 6 or into the annular chamber 5. If preferred, the 65 annular chamber 5 may be formed in the plug instead of the bell-shaped portion, as is illustrated in Fig. 5.

In the operation of the device it is desirable 70 that means should be provided for varying the size of the openings 4 in order that a greater or less quantity of air may be drawn in from the surrounding atmosphere to be mixed with the gas, and I have shown such a means in the burner illustrated in Figs. 3 to 5. 75

Referring more particularly to Figs. 4 and 5, 9 represents a cap adapted to be screwed upon the base 1 and having provided therein a number of perforations 10, the arrangement being such that when the cap is screwed 80 up tightly against the base portion the openings 4 and 10 will not register with each other, and therefore the cap will close the openings 4. If the cap be unscrewed, air will be allowed to enter through the openings 10 and 85 passage 4 in proportion to the size of the chamber 11 formed between the cap and the body. In the operation of the burner the gas will be drawn into chamber 7 from the source of supply and from chamber 7 will 90 pass under considerable pressure through the openings 8 into the passage 6. Inasmuch as the passages 8 are preferably made of smaller area in the aggregate than that of the passage 7, the gas will pass through the openings 8 in 95 considerable pressure and will induce air from the surrounding atmosphere through the openings 4. The gas and air combined passes up through passage 6 and is consumed at the end of the burner. A more perfect combustion 100 is secured with the use of the annular chamber 5, inasmuch as the gas coming through the openings 8 under pressure will be allowed to expand therein and will receive

more air and will be more thoroughly mixed with the same than is the case when the chamber is not used.

The size of the annular mixing-chamber 6 5 and the relative sizes of the gas-inlet passage 8 and annular chamber 5 and the air-inlet passages 4 may be varied in all of the modified forms by sliding the plug 3^a in the body portion. This plug is fitted tightly into the 10 body portion, because it is infrequently necessary to make an adjustment; but the plug is fitted as shown in the drawings, so that this adjustment can be made.

Having thus described my invention, I 15 declare that what I claim as new, and desire to secure by Letters Patent, is—

1. In a gas-burner, a body having an outwardly-flaring flange, a plug fitted in said body within said flange, an air-inlet in said 20 flange, a gas-inlet in said body, and a mixing- passage formed between said plug and said body and in communication with said air and 25 gas inlets, substantially as described.

2. In a gas-burner, a body having an outwardly-flaring flange, a plug in said body within said flange forming a mixing-chamber 25 between said plug and flange, an air-inlet in said flange and a gas-inlet in said body, said inlets communicating with said mixing- 30 chamber, the structure being adapted for varying the proportions of air and gas admitted to said mixing-chamber.

3. In a gas-burner a body having a bell-shaped opening, a plug fixed therein and having 35 a conical head located in said bell-shaped opening, thereby forming an annular passage between the same, an annular chamber at the base of said passage, a chamber in said plug, a gas-inlet to said chamber, and a plurality 40 of passages from said chamber to said annular chamber, substantially as described.

4. In a gas-burner, a body having a bell-shaped opening, a plug fixed therein and having 45 a conical head located in said bell-shaped opening thereby forming an annular passage between the same, an annular chamber at the base of said passage, a chamber in said plug, a gas-inlet to said chamber, a plurality of contracted passages from said chamber to 50 said annular chamber, substantially as described.

5. In a gas-burner, a body having an outwardly-flaring flange, an air-inlet in said flange, a plug movably mounted in said body 55 and having an expanded head, whereby an annular mixing-chamber is formed between said head and said flange, a gas-inlet opening

in said plug, and passages in said plug from said inlet-opening to said mixing-chamber, substantially as described.

6. In a gas-burner a body having a bell-shaped opening, a plug therein containing a chamber and having a conical head located in said bell-shaped opening thereby forming an annular passage, a gas-inlet to said chamber, the structure having a plurality of passages from said chamber to said annular passage and a plurality of openings from the atmosphere to said annular passage, said structure being adapted for varying the proportions of air and gas admitted to the annular passage.

7. In a gas-burner, a body having a bell-shaped opening, a plug therein containing a chamber and having a conical head located in said bell-shaped opening, thereby forming an annular passage between the same, an annular chamber at the base of said passage, a gas-inlet to the plug-chamber, the structure having a plurality of passages from said plug-chamber to said annular chamber, and a plurality of openings from the atmosphere to said annular chamber, said structure being adapted for varying the proportions of the air admitted through the last-named openings.

8. A burner comprising a body having an outwardly-flaring flange provided with an air-inlet, an inner head fitted in the body and forming between the head and flange an annular mixing-chamber, and a gas-inlet to 90 said mixing-chamber.

9. A burner comprising a body portion having an outwardly-flaring flange and an inner head forming between the same an annular mixing-chamber, a gas-inlet to said mixing-chamber and a passage from the air to said mixing-chamber, the structure being adapted for varying the size of the mixing-chamber.

10. In a gas-burner, a body having an outwardly-flaring flange, a plug fitted in said body within said flange, an air-inlet in said flange, a gas-inlet in said body, a mixing- 105 passage formed between said plug and said body and in communication with said air and gas inlets, and means for varying the area of said mixing-passage.

In testimony whereof I affix my signature in presence of two witnesses.

FRANK M. ASHLEY.
